FUSE LINK

John L. Yonkers, Evanston, Ill., assignor to
Joslyn Manufacturing and Supply Company,
Chicago, Ill., a corporation of Illinois

Application September 11, 1944, Serial No. 553,514

5 Claims. (Cl. 200—135)

1

The present invention relates to fuse links and more particularly to improvements in high voltage fuse links adapted for use in open type cut-outs.

Fuse links adapted for use in conventional types of open cut-outs are usually provided with at least one flexible pigtail conductor, the end of which is attachable to a spring arm of the cut-out assembly to place the conductor and at least certain fusible parts of the link under tension. In order to facilitate attachment of the pigtail conductor to the cut-out spring arm, it is common practice to provide a tool receiving or conductor manipulating loop at the end of the pigtail conductor. Typical loop arrangements for this purpose are shown by Fox Patent No. 2,200,496, Lemmon Patent No. 2,208,099 and Fox Patent No. 2,304,250. In all such structures, special parts are required in the formation of the loops, and the loops are of a permanent character in that they cannot be removed or disassembled without destroying a segment of the pigtail conductor. As a result, fuse links employing such loop structures are somewhat costly to manufacture and are not susceptible of uniform use in open type cut-outs of the character mentioned and in those types of cut-outs in which the pigtail conductor is simply clamped to a tensioning element.

It is an object of the present invention therefore to provide a fuse link having a pigtail conductor equipped with an exceedingly simple tool receiving loop at the end thereof.

According to another object of the invention the pigtail loop structure is of such arrangement that it may be easily and rapidly formed at the end of the pigtail conductor and may be just as easily removed from the end of the conductor to produce a corresponding elongation of the conductor.

In accordance with still another object of the invention the loop arrangement is such that a simple washer of appropriate size may be employed both to lock the meeting ends of the loop against disengagement and to act as a shoulder stop against which the tensioning element of a cut-out assembly may bear.

The invention, both as to its organization and method of production, together with further objects and advantages thereof, will best be understood by reference to the following specification, taken in connection with the accompanying drawings, in which:

Fig. 1 illustrates a fuse link of improved construction having a projecting pigtail conductor

2

in which the present improved loop structure may be formed;

Fig. 2 illustrates certain deformation steps involved in the production of the loop structure;

Fig. 3 illustrates the completed loop structure and the manner in which the pigtail conductor may be tensioned between the terminal elements of a cut-out assembly; and

Fig. 4 illustrates the configuration of one of the terminal elements shown in Fig. 3.

Referring now to the drawing, the fuse link there illustrated comprises a metallic tubular housing 10 within which the working parts of the link are housed, and upper metallic contact button 10a and a lower contact sleeve 10b which is insulated from the metal parts 10 and 10a and is electrically and mechanically connected to a pigtail conductor 11. Preferably the component parts of the fuse link and more particularly the working parts enclosed by the tubular housing 10 are of the improved construction and arrangement disclosed and claimed in copending application Serial No. 533,824, filed May 3, 1944, Edward H. Yonkers, and assigned to the same assignee as the present invention. In brief, these parts of the link include at least one fusible element disposed within the housing 10 and electrically and mechanically connected to the contact sleeve 10b and the upper end of the conductor 11, so that when the pigtail conductor is placed under tension by applying a tensioning force between the contact button 10a and a lower part of the conductor, the contact sleeve 10b and any unfused portion of the fusible element will be withdrawn from the tubular housing 10 to produce arc elongation upon rupture of the fusible element.

Referring now more particularly to the present improved pigtail loop structure and the method of forming the same, it is pointed out that the pigtail conductor 11 is in the form of a flexible tube. More specifically, this conductor is comprised of a tubular arrangement of braided wires. Before the loop is formed at the end of the conductor a standard washer 13 having an inner diameter substantially equaling that of the conductor is strung on the conductor and moved therealong to a point above that portion of the conductor from which the loop is to be formed.

As best shown in Fig. 2 of the drawing, in order to form the tool receiving loop at the end of this conductor, the sharp point of an awl-like tool 14 having a uniform diameter slightly greater than the diameter of the conductor 11 is inserted between the wires of the conductor at one

side thereof and at an appropriate intermediate point 15 along the length of the conductor. After the initial insertion is made, the end of the tool is telescoped through the conductor away from the contact sleeve 10b to expand the conductor along a segment 16 of the length thereof. Incident to this operation, the wires at the point of tool insertion are spread apart to form an opening 20 having a diameter equalling the diameter of the tool 14. Following the described operations, the tool 14 may be withdrawn from the conductor 11 without closing the opening 20 or disturbing the expanded condition of the conductor segment 16. To complete the loop, the lower end portion of the conductor 11 is sharply bent at a point 17 therealong to provide a straight portion 18 adapted for insertion into the expanded segment 16 of the conductor. After this bend is made the conductor end 19 is inserted through the opening 20 and the end segment 18 of the conductor is telescoped within the expanded segment 16. In this regard it is noted that the length of the end segment 18 is slightly less than the length of the expanded segment 16, thus providing for seating of the bent conductor portion 17 upon the lower edge of the opening 20.

It has been found that a loop constructed in the manner just described is not readily susceptible of disassembly by tool forces of the character normally applied along the lower portion of the loop in attaching the pigtail conductor to the spring arm of a cut-out assembly. To emphasize this point, one method of supporting the fuse link is illustrated in Fig. 3 of the drawing. As there shown, the link is held between a stationary terminal element 21 and a spring arm 23 of an open cut-out assembly. More specifically, the upper end of the tubular housing 10 is inserted between the upturned tines 22 of the rigidly mounted forked end terminal element 21 so that engagement of the button head contact 10a with the tines 22 provides the sole support for the link. In order to tension the fusible element housed within the tubular member 10, the pigtail conductor 11 is detachably connected at the point 15 therealong to the end of the spring arm 23. In this regard it will be understood that suitable facilities are provided in the cut-out assembly for biasing the outer end of the arm 23 away from the stationary terminal element 21. The spring arm may be of the construction shown in Fig. 4 of the drawing. As there illustrated this arm is provided at its extreme outer end with parts 24 and 25 which extend back from the end of the arm to define conductor receiving slots 26 and 27 upon opposite sides of the arm.

In the assembly of the link upon the cut-out structure the tubular housing 10 is first positioned within the tines 22 of the upper terminal member 21 to support the link from this member. Following this operation the hook at the end of a pigtail manipulating tool is inserted through the loop at the lower end of the pigtail conductor to tension this conductor, and a second tool is used to raise the spring arm 23 to a point such that it is disposed above the point 15 along the conductor. The loop holding tool is now manipulated to move a portion of the conductor which is disposed above the point 15 therealong into one of the slots 26 and 27. Following these operations, the spring arm 23 may be released to thrust against the washer 13 and thus tension the fusible element within the tubular housing 10 and that portion of the pigtail conductor ex-

tending between the contact sleeve 10b and the point 15. In this regard it is noted that the lower surface of the washer 13 abuts the end portion of the pigtail conductor 11 at the bent point 17 therealong such that it is positively restrained in a set position at the point 15 along the conductor. Further, the spring pressure exerted upon the upper surface of the washer 13 by the spring arm 23 serves positively to lock the end segment 18 of the conductor against removal from the expanded segment 16 thereof.

As indicated above, if it desired to use the described fuse link in a cut-out which requires a long pigtail conductor but no loop at the lower end of this conductor, the described loop structure may be quickly and easily removed from the conductor. To this end, the conductor end portion 18 is withdrawn from the expanded conductor segment 16 and straightened by finger manipulation. Following this operation a slight jerk may be applied to the conductor at the ends thereof for the purpose of reducing the expanded segment 16 to its original diameter and of closing the opening 20 in the side of the conductor. After the conductor is thus restored substantially to the configuration shown in Fig. 1 of the drawing, the washer 13 may obviously be withdrawn therefrom.

From the above explanation, it will be apparent that the manipulating loop may be quickly and easily formed at the end of the conductor 11 without the use of specially stamped connecting parts and with but a single tool. It may just as easily be removed from the end of the conductor without using any tools. In this regard it will be understood that when the conductor 11 is in the form shown in Fig. 1 of the drawing the link may be used on any type of cut-out having screw or wedge type facilities for clamping the end of the conductor to a biased extracting element of the cut-out structure, and that the conductor may be cut to any required length. The described loop structure has an additional important advantage in that it may be easily produced by linemen in the field. Further, by appropriate selection of the point 15 along the conductor 11 at which the opening 20 is formed, the seat for the washer 13 may be located different distances away from the button head contact 10a. Thus the link is readily adaptable for use in many different types of cut-out structures having different dimensions between the terminals thereof.

While there has been described what is at present considered to be the preferred embodiment of the invention, it will be understood that various modifications may be made therein which are within the true spirit and scope of the invention as defined in the appended claims.

I claim:

1. In a fuse link, a hollow flexible pigtail conductor electrically connected to a fusible element of the link and provided with an opening in one side thereof at an intermediate point therealong, said conductor also having an end portion telescoped within said intermediate portion through said opening to provide a manipulating loop at the end of said conductor.
2. In a fuse link, a pigtail conductor electrically connected to a fusible element of the link and comprising a tubular arrangement of braided wires, the wires at one side of said conductor being spread apart to provide an opening into the conductor at an intermediate point along the length of the conductor and the end portion of

said conductor being telescoped within said intermediate portion of said conductor through said opening to provide a manipulating loop at the end of said conductor.

3. In a fuse link, a pigtail conductor electrically connected to a fusible element of the link and extending away from one end of the link, said conductor comprising a tubular arrangement of braided wires, the wires at one side of said conductor being spread apart to provide an opening into the conductor at an intermediate point along the length thereof and the wires extending from said opening away from said one end of the link being expanded over a short segment of the conductor to increase the space defined therebetween, and the end portion of the conductor being telescoped within said short segment of the conductor through said opening to provide a manipulating loop at the end of said conductor.

4. In a fuse link, a hollow flexible pigtail conductor electrically connected to a fusible element of the link and provided with an opening in one side thereof at an intermediate point therealong, said conductor also having an end portion telescoped within an intermediate portion thereof through said opening to provide a manipulating loop at the end of said conductor, and a washer strung on said conductor above said loop and adapted to be tensioned against the end portion of the conductor at the point of entry into said opening, thereby to restrain said washer against movement along said conductor beyond said point and to lock the end portion of said conductor within said intermediate portion of said conductor.

5. In a fuse link, a pigtail conductor electrically connected to a fusible element of the link and

extending away from one end of the link, said conductor comprising a tubular arrangement of braided wires, the wires at one side of said conductor being spread apart to provide an opening into the conductor at an intermediate point along the length thereof and the wires extending from said opening away from said one end of the link being expanded over a short segment of the conductor to increase the space defined therebetween, and the end portion of the conductor being telescoped within said short segment of the conductor through said opening to provide a manipulating loop at the end of said conductor, and a washer strung on said conductor above said loop and adapted to be tensioned against the end portion of the conductor at the point of entry into said opening, thereby to restrain said washer against movement beyond said point away from said one end of the fuse link and to lock the end portion of said conductor within the expanded segment of said conductor.
